UNITED STATES PATENT OFFICE.

GEORGE NIERSTHEIMER, OF NEWPORT, KENTUCKY; MARY JEMIMA NIERSTHEIMER EXECUTRIX OF SAID GEORGE NIERSTHEIMER, DECEASED.

HANDLE FOR SHEET-METAL CASKETS.

No. 804,875.

Specification of Letters Patent.

Patented Nov. 21, 1905.

Application filed November 9, 1903. Serial No. 180,435.

To all whom it may concern:

Be it known that I, GEORGE NIERSTHEIMER, a citizen of the United States, and a resident of the city of Newport, in the county of Campbell and State of Kentucky, have invented certain new and useful Improvements in Sheet-Metal Caskets, of which the following is a specification.

One of the principal objects of my invention is to provide new, economical, and acceptable means for equipping burial coffins and caskets with handles.

The several features of my invention and the various advantages resulting from their use conjointly or otherwise will be apparent from the following description and claims.

I will now proceed to describe my invention in detail.

In the accompanying drawings, making a part of this application, and in which similar letters of reference indicate corresponding parts, Figure 1 is a view of a portion of the body of a casket—to wit, the end and the parts near the end—the same being shown in perspective. Fig. 2 is a perspective view of the outer side of a part of the casket and is presented to illustrate an improved construction for the connection of the handles to the casket-body.

The bottom A of the casket is a broad sheet of thin metal. This extends toward each side as far as the point E. An upright sheet A² extends upward as far as the flange A⁴ and there is provided with a horizontal flange A³, extending outwardly. An ornamental basal edge molding B is present at the outer edge of the bottom on every side, and this gives to the base a symmetrical appearance. This basal ornament consists of a bottom B², which is preferably one with the bottom A, and a side B³, the latter representing a molding. At the location B⁴ the molding is flat and comes against the flange A³, heretofore mentioned, and is there soldered or otherwise securely fastened thereto. From this location the sheet metal of the molding is continued upward and constitutes the metal side C of the casket. As it is a feature of the construction that stiffening-pieces of wood shall be combined with the thin metallic sheet, I form the side sheet C so as to receive the main side wooden piece or strip or panel I, to wit: The sheet metal is bent in at C², then extends up, and is then bent

out at C³. It is then extended up and for ornamental purposes is bent out and around at 55 C⁴. It is next formed to receive a top stiffening-rail K, preferably of wood and preferably in one piece as far as the ends of the casket. The end is composed of additional pieces. Where the end is not curved or made of faces, 60 the end section is usually in one piece. In the drawings the end of the casket has side faces F² F³ and an end F. The formation of the sheet metal to properly embrace this rail consists in the upward extension C⁶ and the top C⁷ and the 65 downward extension C⁸. Within the parts C⁶, C⁷, and C⁸ of the bent sheet lies the top rail K. The panel I is secured to the plate C by nails driven through the wood and metal and bent down on the inner side of the metal and cov- 70 ered with solder; but it can be secured by screws, &c. The particular means for securing the wood to the metal may be varied at pleasure. Between the panel I and the rail K is another stiffening piece or rail of wood J. 75 This rests on the bend C³ and extends to the body or molding C⁵. This rail J lies inside of the part C⁴ of the metal wall C. It is preferably secured by nails, and while the inner ends are clenched they are not covered with 80 solder. At each lower corner where the sheet-metal bottom and the sheet metal join there is located a beam or strip H H, preferably secured by nails. These beams and rails H, I, J, and K are also present at each end and 85 serve to impart to the bottom and sides and ends of sheet metal the requisite stiffness against lateral flexure transverse to the length of these stiffening-pieces.

In case the casket requires bracing or 90 strengthening or beautifying structurally or otherwise the same is to be done by suitable means in any proper manner.

I provide a novel mode of connecting the handles R to the casket. These handles may 95 be of the old-fashioned kind; but their escutcheon parts R² are formed with dovetail recesses R³. These embrace a bar R⁴ of a dovetail shape in cross-section. This bar R⁴ is secured to the side of the casket, preferably 100 to the wooden rail I. Such a construction enables the escutcheons to be readily located in place on the coffin, and thus attached thereto. Although, as heretofore suggested, the handles may be connected rigidly to the lug 105 or escutcheon portions, the handles are pref-

erably secured to the lug or escutcheon portions R² by a hinge connection. One form of such hinge connection is illustrated in the drawings. The handles need not be put on the

- 5 coffin during any transit of the latter, especially prior to receiving the corpse. When needed, the escutcheons of the handles can be slipped onto the bar, and thus the handles be put in place. The handles can be prevented
10 from slipping by a nail or nails, screw or screws connecting the escutcheon to the wood.

Of course the wooden lining is secured to the metal in a suitable manner, and where this lining is of two or more pieces the same
15 are firmly united.

The device for connecting the handle to the coffin-body, although primarily designed for a coffin made of metal, either in whole or in part, is also applicable to coffins of other materials and makes, and I claim its application
20 to such other coffins.

It is to be understood that the terms "casket" and "coffin" are used interchangeably in this specification and in the claims. It is
25 to be understood that the word "casket" as herein used includes the various kinds of coffins and of burial-caskets to which my improvements are severally or jointly applicable. Where the rails or strips are alluded to as
30 "rail" or "strip" in the claims, it is to be interpreted as the same made up of two or more pieces wherever the said interpretation is necessary to effectuate the feature or features of the claims.

35 What I claim as new, and of my invention, and desire to secure by Letters Patent, is—

1. In a coffin, the combination of a sheet-metal body and the wooden panel I and dovetail projection or projections, and the handles
40 having lugs or escutcheons provided with dovetail recesses adapted to receive the dovetailed projection or projections, and thereby connect the handle to the coffin-body, substantially as and for the purposes specified.

45 2. In a coffin, the combination of a body and

a dovetail projection or projections, and the handle having dovetailed lugs or escutcheons, adapted to receive and embrace the same, substantially as and for the purposes specified.

3. In a coffin, the combination of a sheet-metal body and the wooden panel I and dovetail projection or projections, and the handles having lugs or escutcheons provided with dovetail recesses adapted to receive the dovetailed projection or projections, and thereby connect the handle to the coffin-body, the handle being hinged to the said lug or lugs, substantially as and for the purposes specified. 50
55

4. In a coffin, the combination of a body and a dovetail projection or projections and the handle having dovetailed lugs or escutcheons, adapted to receive and embrace the same, the handle being hinged to the said lug or lugs, substantially as and for the purposes specified. 60

5. In a coffin, the combination of a body and a separable handle, and dovetail connections between said body and said handle, for enabling the handle to be readily put into place, and be held there, and vice versa, substantially as and for the purposes specified. 65
70

6. In a coffin, the combination of a sheet-metal side made substantially as described, and a wooden panel, and a separable handle, and dovetail connections between said body and said handle, for enabling the handle to be readily adjusted to position, and be secured thereto, and vice versa, substantially as and for the purposes specified. 75

7. In a coffin, the combination of a body, panel, a handle, and dovetail connections between the handle and the panel, substantially as and for the purposes specified. 80

In testimony whereof I have signed my name to this specification in the presence of two subscribing witnesses.

GEORGE NIERSTHEIMER.
